UNITED STATES PATENT OFFICE.

JOSEF RUDOLF, OF GERA, GERMANY.

APPARATUS FOR WATERPROOFING AND FINISHING TEXTILE MATERIAL.

SPECIFICATION forming part of Letters Patent No. 653,702, dated July 17, 1900.

Original application filed March 26, 1898, Serial No. 675,283. Divided and this application filed August 22, 1899. Serial No. 728,123. (No model.)

To all whom it may concern:

Be it known that I, JOSEF RUDOLF, a subject of the Emperor of Germany, and a resident of 31 Thalstrasse, Gera, in the Principality of Reuss and Empire of Germany, have invented a new and useful Improvement in Apparatus for Waterproofing and Finishing Textile Material, of which the following is a specification.

10 My invention relates to an improvement in apparatus for waterproofing and finishing cloth fabrics, felt, paper, leather, skin, and similar stuffs to protect them against stains and moths.

15 Heretofore it has been the practice in waterproofing and finishing such goods to apply stearin, wax, or analogous solid substances by dissolving said substances in benzole, benzin, &c., and then immersing the goods in 20 the solution thus produced, or to allow a hot roller to rotate against such solid substances and then pass the goods against the roller or form plates or cylinders of such substances and allow the goods to rest on them. The 25 first treatment has the disadvantage of being too costly, owing to the employment of means for dissolving the substances and is also endangered by fire. In the second and third treatment it is difficult to accomplish a uniform 30 form and regular taking up of the substances.

My improvement comprises a heating device, a trough or reservoir adapted to receive an emulsion of substances insoluble in water, (as stated in my application, Serial No. 675,283, 35 for United States Letters Patent, filed March 26, 1898, of which this application is a division,) an engraved feed-roller dipping into the trough or reservoir, a trimming-knife for the feed-roller for removing the surplus emulsion, a cold pressure-roller, under which the material treated is pressed against the feed-roller, having a padding, an idle roller, an endless cloth band suspended from the idle roller and working under the pressure-roller, 45 a protecting-strip guided between the feed and pressure rollers and led from idle rollers and tension-bars, and rollers and tension-bars for the material treated, as hereinafter described and claimed.

50 In order that my invention may be fully understood, I will proceed to describe it with

reference to the accompanying drawings, in which—

Figure I is a view of the apparatus which I employ in carrying out my invention. Fig. 55 II is a vertical section of the same on the line II II, Fig. I.

1 is a gas-pipe having burners 2, over which is located a reservoir or trough 3, heated by the ignited gases issuing from the burners. 60 This trough or reservoir is supplied with an emulsion of solid hydrocarbons—such as paraffin, ozocerate, or similar substances, as stearin and palmitin, or with an emulsion of zinc, calcium, aluminium stearates or palmitates, 65 vegetable wax, beeswax, rosin, &c. These substances are very finely separated in hot water or other fluid while in their solid condition, either singly or mixed with each other, by means of an emulsion centrifugal machine, 70 whereby an emulsion is produced in which the solids are finely separated and similar in consistency to the fat in milk. Located within in the reservoir or trough and dipping into the heated emulsion is a feed-roller 4, having 75 an engraved or cut surface 4^a, which takes up and transfers the emulsion to the material to be waterproofed or finished.

5 is an adjustable trimming-knife for removing the surplus emulsion from the feed-roller and also for regulating the thickness of the thin film of emulsion issuing therefrom and deposited on the fabric. Located over the feed-roller and bearing thereon is the main cylindrical pressure-roller 6, which 85 is cold and under which the material to be treated is passed to receive a thin film of the emulsion from the feed-roller. The pressure-roller is provided with a padding, providing an inner cushion or covering 7. Over this 90 cushion runs an endless band 8, of thick cloth, extending from an idle roller 9. For the protection of this band, so that it may not be smeared at its sides, there runs with it a thin strip of cotton 10, which is guided by rollers 95 11, 12, and 13, and passes between tension-bars 14 and 15.

16 represents the material being operated upon, which passes from a roller 16^a under an idle roller 17, between tension-strips 18 100 and 19, and then between the feed-roller 4 and the pressure-roller, where it receives its

coating of waterproofing or finishing emulsion in the form of a thin film. It will be apparent that only the emulsion contained in the cuttings or engravure of the feed-roller 5 is transferred to the material under treatment.

By my apparatus the taking up of the emulsion is accomplished uniformly, owing to the employment of the padding and the bands 10 referred to. According to the material acted on and according to the necessity of applying more or less of the emulsion the surface of the feed-roller is held strongly or lightly against the material. The material treated 15 has the emulsion melted into it from the hot feed-roller, as the temperature must be above 80° centigrade.

Having thus described my invention, the following is what I claim as new therein and 20 desire to secure by Letters Patent:

An apparatus for waterproofing and finishing textile material while permitting the material to remain porous, comprising a heat-

ing device, a trough located over the heating device, for containing the emulsion to be 25 heated and applied, an engraved feed-roller dipping into the heated emulsion, a trimming-knife for removing the surplus emulsion from the engraved feed-roller, a cold pressure-roller having a padding providing a cushion 30 for the fabric, a tension device through which the fabric is drawn on its passage between the engraved feed-roller and the pressure-roller, a tension device through which a thin protecting-strip is drawn on its passage 35 between the fabric and the pressure-roller, an idle roller and an endless cloth band working over the idle roller and between the padding of the pressure-roller and the protecting-strip; substantially as described. 40

The foregoing specification signed at Gera this 19th day of July, 1899.

JOSEF RUDOLF.
